UNITED STATES PATENT OFFICE

114,022

DESIGN FOR A COMBINATION SLIDE FASTENER AND MESH COVER THEREFOR

Ralph Kay, New York, N. Y.

Application February 7, 1938, Serial No. 74,949

Term of patent 7 years

To all whom it may concern:

Be it known that I, Ralph Kay, a citizen of the United States, residing in New York, county of Bronx and State of New York, have invented a new, original, and ornamental Design for a Combination Slide Fastener and Mesh Cover Therefor, of which the following is a specification, reference being had to the accompanying drawing, forming part thereof.

Figure 1 is a front elevation of a combination slide fastener and mesh cover therefor showing my new design.

Figure 2 is a cross-sectional view, the section being taken as on line 2—2 in Figure 1.

Figure 3 is a side elevation of the combination slide fastener and mesh cover therefor partly in open position.

I claim:

The ornamental design for a combination slide fastener and mesh cover therefor, substantially as shown and described.

RALPH KAY.
